UNITED STATES PATENT OFFICE.

WILLIAM B. FOLGER, OF CINCINNATI, OHIO.

COMBINED GAS AND WATER COCK FOR WATER-HEATERS.

SPECIFICATION forming part of Letters Patent No. 690,413, dated January 7, 1902.

Application filed May 5, 1900. Serial No. 15,567. (No model.)

To all whom it may concern:

Be it known that I, WILLIAM B. FOLGER, a citizen of the United States of America, and a resident of Cincinnati, in the county of Hamilton and State of Ohio, have invented certain new and useful Improvements in a Combined Gas and Water Cock for Water-Heaters, of which the following is a specification.

The object of my invention is a combined water-valve and gas-cock for those heaters in which water is heated by ignited gas, formed in a single casting, by means of which the gas is turned on and kept so turned on by the flow of water through the water-valve, even though the pressure of the flow be low, is turned off effectually when the flow ceases, and in which the parts do not stick nor work hard after standing. This object is attained by the means described in the annexed specification and illustrated in the accompanying drawings, in which—

Figure 1 is a front elevation of a combined water-valve and gas-cock embodying my invention. Fig. 2 is a central vertical longitudinal sectional view of the same. Fig. 3 is a transverse sectional view of the same, taken upon line xx of Fig. 2 looking toward the left. Fig. 4 is a front elevation of a modification.

Referring to the parts, the cylindrical casing A of the water-valve a and the casing B of the gas-cock are formed in a single casting. Casing A has a lower externally-screw-threaded extension forming an inlet a' to receive a water-supply pipe, and a lateral externally-screw-threaded extension forming outlet a^2 to receive the pipe leading into a water-heater. (Not shown.) The top of the casing is closed by a cap a^3 . Within the cylindrical bore of the casing is the piston-valve a , which has a stem a^4 , extending up into cap a^3 , and a downwardly-extending stem a^5 , upon the end of which is a nut a^6 to hold thereon a loose cylindrical weight a^7 . Between piston a and weight a^7 is a washer a^8 , which has a downwardly-projecting annular flange a^9 . When the water is turned on, it throws weight a^7 against washer a^8 , so that the outer beveled edge of the weight bearing against flange a^9 spreads it outward and makes it fit snugly against the walls of the casing. Within casing A and journaled in its walls is a trans-

verse shaft a^{10} , upon which is secured a lever a^{11} , whose end extends into a slot a^{12} in stem a^4 . Shaft a^{10} extends through the front of casing A and outside of the casing has a lever a^{13} secured to it. A by-pass a^{14} forms communication between the upper part of the casing and outlet a^2 to allow any water which leaks past piston a into the upper part of the casing to pass out, so that it creates no back pressure when piston is raised.

Casing B of the gas-cock has a lateral internally-screw-threaded extension forming inlet b to receive a gas-supply pipe, and a rearwardly-extending externally-screw-threaded extension forming outlet b' to receive the gas-pipe leading into the jets in the heater. Casing B has a transverse bore, which is to receive a conical plug-valve b^2 and from which extends a lateral passage b^3 into the inlet b , a downward passage b^4 into the outlet b' , and an upper narrow passage b^5 into the secondary plug-valve b^6 , which regulates the lighter b^7 , which is kept burning constantly. Plug-valve b^2 has an angular passage b^8 to register in the open position with passages b^3 and b^4 , and upon its front end is secured a lever b^9 , which is coupled to lever a^{13} by a link b^{10} . When piston a is raised by the water, lever a^{13} is rotated to the right, communicating a similar movement through link b^{10} to lever b^9 , which rotates plug-valve b^2 , so that passage b^8 places inlet b in communication without outlet b' turning the gas on in the heater. The valve and cock are returned to their normal positions by a weight C, attached to the end of shaft a^{10} .

Secondary plug-valve b^6 has secured upon its end a lever b^{11} , which is connected by a link b^{12} to lever b^9 . When levers a^{13} and b^9 are rotated toward the right, as above described, turning on the water and the gas within the heater, secondary plug-valve b^6 is rotated so that channel b^{13} in it puts passage b^5 in direct communication with lighter b^7 , sending a greatly-increased flow of gas into it, so that its flame shoots out across the jets in the heater to ignite the gas issuing therefrom. When water-valve and gas-cock are shut off, the gas passes into the lighter from the inlet by means of contracted channels b^{14} and b^{15} in the secondary plug, as shown in Fig. 2. To form a passage into the lighter while plug

b^9 is turning, the latter has a semicircular groove b^{16} extending around it, as shown in Fig. 2.

In the modification shown in Fig. 4 in place 5 of levers a^{13} and b^9 shaft a^{10} and plug b^2 have intermeshing cog-wheels a^{15} and b^{17} attached to their ends, which are coupled by links a^{16} and b^{18} to a slip-block d , which slides on a rod d' , secured to the casting. Upon the rod is 10 likewise a sliding weight D , which returns valve a to its normal position and closes the gas-cock when the flow of water is cut off.

As seen in Fig. 2, the piston and the washer in their lowered position fit the water-cylinder loosely, so that there is little tendency in 15 them to "stick" after standing. The jar of weight a^7 , when it is thrown upward against the under side of piston a , overcomes whatever of this tendency there may be in the 20 parts. The pressure of the flow necessary to open and keep the water-valve open needs to be but little more than that of the combined weights of the weights a^7 and C , and when the flow ceases these weights bring the 25 parts effectually to their normal position shown in Fig. 2. This combined with the simplicity of construction and the absence of packed joints overcomes any danger of leakage either from gas or water.

30 What I claim is—

1. In a combined water-valve and gas-cock a water-supply pipe, a casing interposed therein, a piston within the casing to be carried to and held in its open position by the 35 flow of water in the pipe and having a downwardly-projecting stem, a weight mounted loosely upon the stem to be thrown upward against the valve by the pressure of the water when turned on, a gas-supply pipe, a casing interposed therein, a valve in the casing 40 for regulating the flow of gas, and means for coupling the piston and the valve whereby the flow of water controls the flow of gas, substantially as shown and described.

2. In a combined water-valve and gas-cock 45 a water-supply pipe, a casing interposed therein, a piston within the casing to be carried to and held in its open position by the flow of water in the pipe and having a downwardly-projecting stem, a washer upon the 50 stem below the piston, a cylindrical weight retained loosely on the stem to be thrown upward against the washer by the water when it is turned on, a shaft journaled in the casing, means for coupling the shaft and the piston whereby the piston rotates the shaft, a gas-supply pipe, a casing interposed therein, a rotatable plug-valve in the casing for opening and closing off the flow of gas through the 55 pipe, and means for coupling the rotating shaft and the plug-valve whereby the rotation of the shaft caused by the flowing of the water in its case is communicated to the plug-valve to turn on the gas, substantially as shown and described. 65

3. In a water-valve and a gas-cock the combination of a piston to be raised by inflowing water, a shaft to be rotated by the raising of the piston, a lever attached to the end of the shaft, a rotating plug-valve for opening and 70 shutting off the flow of gas through the cock, a second lever attached to the plug-valve, means for coupling the levers to communicate the motion from one to the other, a lighter, a channel for supplying it continuously with 75 gas, a secondary plug-valve interposed in the channel having an enlarged and a contracted opening therein through which the gas passes to the lighter, a lever secured to the secondary plug-valve, a link connecting it with said second lever for rotating the secondary plug to put the lighter in direct communication with the enlarged channel therein, substantially as shown and described. 80
